UNITED STATES PATENT OFFICE.

AUGUST H. BUTCHECK AND ALFRED H. LAWTON, OF PORTLAND, OREGON.

SHAVING-MUG.

1,158,785.

Specification of Letters Patent. Patented Nov. 2, 1915.

Application filed December 13, 1913. Serial No. 806,399.

To all whom it may concern:

Be it known that we, AUGUST H. BUTCHECK and ALFRED H. LAWTON, citizens of the United States, residing at Portland, in the county of Multnomah and State of Oregon, have invented certain new and useful Improvements in Shaving-Mugs, of which the following is a specification.

Our invention relates to fountain shaving mugs of a type that is so constructed that a measured amount of liquid soap will pass into the bowl portion from the reservoir which surrounds said bowl.

The object of this invention is to provide a device of this kind that is simple in construction, durable, efficient in action, and comparatively inexpensive in manufacture;—and further to provide a shaving mug with its elements so combined that only as much soap as is required to shave one person will pass into the bowl portion when the plunger is operated.

With these and other useful objects in view, the invention consists of certain novel features of construction, combinations of elements, and arrangements of parts to be hereinafter fully set forth and particularly pointed out in the appended claims.

In order to clearly comprehend this invention and the art to which it relates, reference must be made to the accompanying drawing which forms part of this application, on which:—

Figure 1 is a plan view of the invention; Fig. 2 is a vertical section of same, taken on line A A, of Fig. 1, and Fig. 3 is a similar view taken on line B B, of Fig. 1; the cylinder being shown in perspective.

Now referring to the drawing, of which like characters of reference indicate like parts, the numeral 2 indicates the body portion of the mug to which is integrally attached a bowl 3; formed intermediate said bowl and body portion is a soap reservoir 4 which passes from the top portion of the mug where the bowl is connected to the body portion, to false-bottom 5. Passing from bottom 6 of the mug upwardly into reservoir 4, is an angular cylinder 7 with an aperture 8 in the upper end thereof through which passes rod 9;—said rod connecting to plunger 10, and passing upwardly through boss 11 which is formed intermediate handle 12 and body portion 2, and screwing into knob 13. Encircling the rod intermediate boss 11 and knob 13, is a coil-spring

14 which serves to bring plunger 10 into its normal position after it has pressed said plunger downwardly. It will be noted that knob 13, screws to rod 9 and serves to regulate the tension of the coil-spring 14, as well as governing the downward thrust of plunger 10. Passing from cylinder 7 intermediate the false-bottom 5 and bottom 6 is a pipe 15 which runs transversely of said bottom, vertically of the body portion 2, and terminates at aperture 16 which opens into bowl 3 for the purpose of allowing the liquid soap to pass into said bowl.

In bottom 6 is an aperture 17 which opens into cylinder 7 which serves as a means for filling reservoir 4 with liquid soap, which passes into said reservoir through port 18; said port also serving as an outlet to cylinder 7 when plunger 10 is pressed downwardly for the purpose of forcing the soap upwardly through pipe 15 and into the bowl. When the reservoir is filled to capacity, a cork 19 is placed into aperture 17 to prevent the liquid leaking out when it drops into the cylinder.

In order to operate our invention, reservoir 4 is filled with liquid soap, plunger 10 is pressed downwardly through the medium of rod 9 to a predetermined distance, which forces the soap upwardly into pipe 15, from where said soap passes through aperture 16 into bowl 3. These operations measure out approximately enough soap to produce the required amount of lather to be used in shaving one person.

Another feature of our invention is the fact that it is sanitary and economical, as it provides only as much soap as is required for one person; after shaving, the bowl may be thoroughly cleaned and prepared for another person, a desideratum of importance in public barber shops.

Our invention may be constructed of any material and made any size deemed suitable for all the requirements of such a device, and while we have illustrated and described a preferred form of construction, and combinations of elements considered essential in materializing the same, we wish to include in this application, all mechanical equivalents and substitutes that may be fairly considered to lie within the scope and purview of our invention as defined in the appended claims.

Having thus fully described our invention so that others skilled in the art to

which it appertains may be enabled to construct and use the same, what we claim and desire to secure by Letters Patent, is:—

1. In a device of the character described, 5 a mug consisting of a body portion and a bowl attached to said body portion, said body and bowl forming a reservoir therebetween, means to cause the flow of liquid from the reservoir to the bowl, and means 10 to vary the amount of flow upon the operation of said first mentioned means, substantially as set forth.
2. In a device of the character described, 15 a mug consisting of a body portion, a bowl integral with said body portion, said bowl and body portion forming a reservoir therebetween, a cylinder passing from the bottom of the mug upwardly to a predetermined distance, a plunger adapted to operate in said cylinder, said cylinder having an aperture connecting with the reservoir, a rod attached to the plunger and passing without the body portion, means attached to the outwardly extending portion of said rod 20 to regulate the stroke of the plunger, and soap-conveying means passing from the cylinder to the bowl, substantially as set forth.
3. In a device of the character described, 25 a body portion, a bowl integral with said body portion, said bowl and body portion forming a reservoir therebetween, a cylinder below the bowl within the reservoir, and a portion of said cylinder opening into the reservoir, a plunger to operate in the cylinder, means to actuate said plunger, a pipe to convey liquid soap from said cylinder to the bowl, and means to predetermine the amount of said liquid soap forced by said plunger from the cylinder to the bowl, for 35 the purposes set forth.
4. In a shaving mug, a body portion, a 40

bowl integral with said body portion, said bowl and body portion forming a reservoir therebetween, a cylinder passing from the bottom of the mug upwardly to a predetermined distance and having a portion thereof opening into the reservoir, a plunger adapted to operate in said cylinder, a rod attached to the plunger and passing without the body portion, a knob screwed to the free end of the outwardly projecting portion of said rod, a spring encircling the rod intermediate the knob and body portion, said knob serving as a means by which said rod may be pressed downwardly to operate the plunger to a predetermined distance, and a pipe connected with the cylinder and bowl to convey soap from the cylinder to the bowl, for the purposes set forth.

5. In a device of the class described, a 60 body portion, a bowl mounted in said body portion said body and bowl forming a reservoir therebetween, a cylinder below the bowl extending in said reservoir and having an aperture opening thereto, and a pipe 65 connecting with the lower part of said cylinder and with said bowl for leading liquid soap from the cylinder to the bowl, and a reciprocable plunger in said cylinder for pumping liquid, said cylinder having an 70 aperture in its lower end which is normally closed and whereby liquid may be fed into said reservoir through said cylinder and said first mentioned aperture.

In testimony whereof we hereunto affix 75 our signatures in the presence of two witnesses.

AUGUST H. BUTCHECK.
ALFRED H. LAWTON.
